Fig. 1. Safford's Design for an Electric Machine Winding

Dec. 1742.

Joseph A. Safford, of Winchester, Mass.
Letters Patent No 1742, dated. March 24, 1863

The schedule referred to in these Letters Patent and making part of the same

To all Persons to whom these Presents shall come:

Be it known that I, Joseph A. Safford,

(a Citizen of the United States of America, and a resident of Winchester,
in the County of Middlesex, and State of Massachusetts) have invented

2
Dec. 1742

or produced a new and original design for the stand or frame of an Eyelet Machine; and I do hereby declare the same to be described in the following specification and represented in the accompanying drawings, of which.

Figure 1. is a top view;

Figure 2. a side elevation, and

Figure 3. a front elevation, of it

Figure 4. is a vertical section of it.

The stand has a flat base A, approximating in form to a triangle as shown in Figure 1. From this base rises a post B, which extends vertically a short distance above a knee, C, which projects from it horizontally and subsequently is bent vertically as shown in the drawings. Between the two extremities of the knee the post inclines with a bend, a, and finally is curved horizontally and is joined to the top of the knee, C. The two circular lips of a hinge project from the angle of junction of the knee and post. Cylindrical projections D. E. extend downward from the foot and knee and in a vertical line with each other, they being intended as guides for the eyelet punch and are bored suitably to receive it.

Furthermore, the base A is formed with a raised projection or platform, e, the top view of which is represented in red lines in Figure 1. Through the base and this platform, there is a rectangular opening, f, there being similar openings made through the knee, C, and the post, B, and directly over the opening f.

The base plate is made with semi-circular or curved projections h, h, on each side of it through which screw holes are made.

I claim the said design for the stand of an Eyelet Machine.

Witnesses.

R. H. Eddy

J. P. Hale Jr.

11/5/18 J. A. Safford.
